UNITED STATES PATENT OFFICE.

MARC H. DAUDY, OF PHILADELPHIA, PENNSYLVANIA, ASSIGNOR TO NORTH AMERICAN LACE COMPANY, OF PHILADELPHIA, PENNSYLVANIA, A CORPORATION OF PENNSYLVANIA.

DESIGN FOR LACE.

Application filed July 23, 1924. Serial No. 10,241. Term of patent $3\frac{1}{2}$ years.

To all whom it may concern:

Be it known that I, MARC H. DAUDY, a citizen of the Republic of France, residing in Philadelphia, Pennsylvania, have invented a new, original, and ornamental Design for Lace, of which the following is a specification, reference being had to the accompanying drawing, forming part thereof, in which the figure is a face view of a piece of lace illustrating my new design.

The heavier lines of the design indicate a color contrasting with a color shown by the lighter lines. The heading is also of a color contrasting with the color of the open work of the design.

I claim:

The ornamental design for lace, substantially as shown and described.

MARC H. DAUDY.
